UNITED STATES PATENT OFFICE

152,267

DESIGN FOR A FRONT PANEL FOR A TELEVISION RECEIVER OR THE LIKE

Vernon A. Kamin, Elgin, Ill., assignor to Motorola, Inc., Chicago, Ill., a corporation of Illinois

Application January 9, 1948, Serial No. 143,632

Term of patent 14 years

(Cl. D56—4)

To all whom it may concern:

Be it known that I, Vernon A. Kamin, a citizen of the United States, residing at Elgin, in the county of Kane, State of Illinois, have invented a new, original, and ornamental Design for a Front Panel for a Television Receiver or the like, of which the following is a specification, reference being had to the accompanying drawings forming a part thereof, in which:

Fig. 1 is a front elevational view of the front panel for a television receiver embodying my new design;

Fig. 2 is a top plan view thereof;

Fig. 3 is a cross sectional view through approximately the center of the panel;

Fig. 4 is a back elevational view of the panel; and

Figs. 5, 6, 7 and 8 are cross sectional views along the lines 5—5, 6—6, 7—7 and 8—8, respectively, of Fig. 1.

I claim:

The ornamental design for a front panel for a television receiver or the like, substantially as shown.

VERNON A. KAMIN.
